(57) **CLAIM**

The ornamented designs in medical training trolley, as shown and described.

DESCRIPTION

FIG. 1 is a front view of a medical training trolley according to a first embodiment;

FIG. 2 is a left side view of the medical training trolley of the embodiment of FIG. 1;

FIG. 3 is a right side view of the medical training trolley of the embodiment of FIG. 1;

FIG. 4 is a bottom view of the medical training trolley of the embodiment of FIG. 1;

FIG. 5 is a left side view of the medical training trolley of the embodiment of FIG. 1 in the open position;

FIG. 6 is a front view of the medical training trolley of the embodiment of FIG. 1 in the open position;

FIG. 7 is a front view of a medical training trolley according to a second embodiment;

FIG. 8 is a left side view of the medical training trolley of the embodiment of FIG. 7;

FIG. 9 is a right side view of the medical training trolley of the embodiment of FIG. 7;

FIG. 10 is a bottom view of the medical training trolley of the embodiment of FIG. 7;

FIG. 11 is a left side view of the medical training trolley of the embodiment of FIG. 7 in the open position;

FIG. 12 is a front view of the medical training trolley of the embodiment of FIG. 7 in the open position;

FIG. 13 is a front view of a medical training trolley according to a third embodiment;

FIG. 14 is a left side view of the medical training trolley of the embodiment of FIG. 13;

FIG. 15 is a right side view of the medical training trolley of the embodiment of FIG. 13;

FIG. 16 is a bottom view of the medical training trolley of the embodiment of FIG. 13;

FIG. 17 is a left side view of the medical training trolley of the embodiment of FIG. 13 in the open position;

FIG. 18 is a front view of the medical training trolley of the embodiment of FIG. 13 in the open position;

FIG. 19 is a front view of a medical training trolley according to a fourth embodiment;

FIG. 20 is a left side view of the medical training trolley of the embodiment of FIG. 19;

FIG. 21 is a right side view of the medical training trolley of the embodiment of FIG. 19;

Figure. 22 is a bottom view of the medical training trolley of the embodiment of FIG. 19;

FIG. 23 is a left side view of the medical training trolley of the embodiment of FIG. 19 in the open position; and,

FIG. 24 is a left side view up the medical training trolley of the embodiment of FIG. 19 in the open position.
